UNITED STATES PATENT OFFICE.

GEORGE M. RHONEMUS, OF INDEPENDENCE, MISSOURI.

DIRT-COLLECTOR FOR WASHTUBS.

1,188,680.

Specification of Letters Patent. Patented June 27, 1916.

Application filed March 13, 1916. Serial No. 33,723.

To all whom it may concern:

Be it known that I, GEORGE M. RHONEMUS, a citizen of the United States, residing at Independence, in the county of Jackson and State of Missouri, have invented a certain new and useful Improvement in 5 Dirt-Collectors for Washtubs, of which the following is a specification.

My invention relates to improvements in 10 dirt collectors for wash-tubs.

The object of my invention is to provide a wash tub with a perforate false bottom under which, during the washing of clothes, the dirt therefrom will be collected.

15 A further object of my invention is to provide a dirt collector of novel construction which may be readily fitted in or removed from wash tubs now in use.

Still another object of my invention is to 20 provide a novel dirt collector adapted to be removably fitted in a wash tub, which may be cheaply manufactured, which is durable and not liable to injury, which is sanitary, and readily cleaned, and which will not tear 25 or otherwise injure the clothes, which are washed in the tub which contains the collector.

In addition to its utility in connection 30 with wash tubs, my invention is adapted for use in washing machines and wash-boilers.

The novel features of my invention are hereinafter fully described and claimed.

In the accompanying drawing, which 35 illustrates the preferred embodiment of my invention, as applied to a wash tub, Figure 1 is a central vertical sectional view of a wash tub provided with my improvement. Fig. 2 is a top view of my improved dirt 40 collector shown detached from the tub. Fig. 3 is a side elevation of the same. Fig. 4 is a bottom view of the dirt collector.

Similar reference characters designate 45 similar parts in the different views. Fig. 1 designates the side walls of an ordinary tub having the usual imperforate bottom 2, from which the side walls upwardly diverge.

3 designates the top of a dirt collecting 50 member provided with perforations 4, and preferably concave on its upper side. The dirt collecting member is provided with an annular peripheral downwardly extending flange 5, the outer sides of which preferably 55 converge downwardly so as to be fitted between and against the walls 1 of the tub.

The flange 5 may also rest upon the bottom 2.

For supporting the middle portion of the top 3 of the collector, and for the purpose 60 of providing disconnected compartments between said top and the bottom 2, there are provided one or more annular concentric flanges or partitions 6 which extend downwardly from the under side of the top 3 and 65 rest upon the bottom 2.

The partitions 6 divide the space below the top 3 into a plurality of disconnected compartments with each of which communicate some of the perforations 4. By dividing 70 the space under the collector in the compartments, which are disconnected from each other, the circulation of the water under the collector is impeded, thereby lessening the liability of the dirt passing from the under 75 to the upper side of the collector, so as to again mingle with the clothes. The partitions 6 further serve to strengthen the pan-shaped collecting member.

The top 3 may be provided with a hole 7 80 of sufficient diameter to receive a person's finger so that the collector may be easily lifted from its operative position in the tub. The hole 7 may serve further to receive a supporting hook or nail, not shown, when 85 the device is not in use.

It will be obvious that the pan-shaped collecting member may have the proper contour to enable its being fitted within a receptacle of any shape with which it is to 90 be used.

In the operation of my invention, the collector having been fitted within the tub or other receptacle in which it is to be used, as the clothes are being washed, the dirt 95 therefrom will settle downwardly in the water and will pass through the perforations 4 into the compartments between the imperforate bottom 2 and the top 3 of the collector. After the clothes have been washed, 100 the collector is removed from the tub, upon which the latter may be emptied and cleaned.

As the top 3 is concave, this form imparts strength thereto, and it further causes the larger portion of the dirt falling thereupon 105 to gravitate to and enter the inner compartments, thus preventing the collection of any large amount of the dirt in the lower corner of the tub, and rendering its removal therefrom an easy matter.

I do not limit my invention to the structure shown and described, as modifications,

within the scope of the appended claims, may be made without departing from the spirit of my invention.

What I claim is:—

- 5 1. In a dirt collector for wash tubs, an inverted pan shaped member having a perforate top and provided with an annular downwardly extending partition adapted to rest upon the bottom of a tub, and having an
- 10 annular downwardly converging peripheral flange adapted to be fitted within the side walls of the tub.

2. In a dirt collector for wash tubs, an inverted pan-shaped member having a perforate top concave on its upper side and 15 provided on its under side with an annular downwardly extending partition adapted to rest upon the bottom of a tub, and having an annular downwardly converging peripheral flange adapted to be fitted within the 20 side walls of a tub.

In testimony whereof I have signed my name to this specification.

GEORGE M. RHONEMUS.

Copies of this patent may be obtained for five cents each, by addressing the "Commissioner of Patents, Washington, D. C."
